UNITED STATES PATENT OFFICE.

CURT A. ARENTS, OF ALAMEDA, CALIFORNIA.

FLY-CATCHER.

No. 904,668.

Specification of Letters Patent.

Patented Nov. 24, 1908.

Application filed January 2, 1908. Serial No. 409,042.

To all whom it may concern:

Be it known that I, CURT A. ARENTS, a citizen of the United States, residing at Alameda, in the county of Alameda and State 5 of California, have invented new and useful Improvements in Fly-Catchers, of which the following is a specification.

My invention relates to improvements on my fly catcher illustrated and described in 10 my Patent No. 851,478, dated April 23, 1907, and the object thereof is to provide an improved and cheapened construction for the same which may be made of convenient and inexpensive materials.

15 I accomplish this object by means of the device described herein and illustrated in the accompanying drawings in which:—

Figure 1,—is a sectional elevation of my improved fly catcher. Fig. 2,—is a view 20 similar to Fig. 1 of a modified form of device. Fig. 3,—is a section of the same taken on line 3—3 of Fig. 2. Fig. 4,—is a perspective detail of the inner end of the tape coiled within the catcher. Fig. 5,—is a perspective detail of the tape guide employed 25 in the form shown in Fig. 2. Fig. 6,—is a perspective detail of the tape guards mounted in the opening at the top of the catcher receptacle. Fig. 7,—is a perspective detail 30 of the tape supporting frame utilized in the form of catcher shown in Fig. 1.

Referring to the drawings, 10 designates 35 a receptacle which may be in any preferred configuration but is conveniently circular as illustrated. This receptacle is composed of a body member 11 and a cover 12 which fits tightly thereon to prevent sticky liquid 13 from escaping from the receptacle. A bail 14 is provided which is pivotally attached 40 to the receptacle as at 15 by being passed through the walls thereof and upset on the inside as shown in Fig. 2. By means of this bail the receptacle is adapted to be suspended from any convenient support, as a 45 hook 16 attached to ceiling 17. Pivotal points 15 are preferably eccentrically arranged on the receptacle so that the receptacle will normally stand in the normal position shown without the necessity of placing 50 the articles within the same to hold it in that position. These pivots however may be placed at any point on the receptacle and the articles within the same so arranged as to hold the receptacle in its normal upright position.

Located near the top of the receptacle and

in peripheral wall 18 thereof is a slotted opening 19 through which a tape 20 emerges from the receptacle. Arranged on the sides of slot 19 are resilient guards 21 which cover 60 the longitudinal edges of the slot and press against tape 20 to remove therefrom any superfluous liquid 13 which may adhere thereto. These guards are preferably composed 65 of spring metal and are bent into a curved formation on the inside of the receptacle so as to resiliently press against the inner walls of the receptacle and thus clamp themselves securely in place. A further purpose of these guards is to provide a smooth curved 70 surface over which tape 20 may pass without any liability of being torn or abraded.

Tape 20 is preferably loosely coiled within receptacle 10 on a stud 26 so as to turn freely thereon. Stud 26 forms an integral part of 75 a resilient wire frame 27 which is circular in shape and is adapted to expansively fit in the receptacle and thus hold the roll of tape in the position shown. On the other end of frame 27 a stud 28 is provided over which a 80 roller sleeve 29 is preferably placed and around which tape 20 passes. The tape passes from roller 29 out of the receptacle through aperture 19 where it hangs downwardly to any desired extent. 85

It will be understood that frame 27 may be placed in any desired position in the receptacle, a preferred position being that with stud 28 directly underneath opening 19 so that the tape passes vertically between the 90 stud and the opening and is thereby uniformly exposed on both sides to the sticky liquid. Further stud 26 may be dispensed with and the roll of tape be allowed to rest 95 loosely in the receptacle and to take any position therein.

In Figs. 2 and 3 a modified form of catcher is shown in which the roll of tape is mounted loosely within the receptacle. With this construction I may employ either the frame 100 27 shown in Fig. 1 or a tape guide 23 shown in Figs. 2, 3 and 5, this guide being preferably formed of a flat piece of metal 24 bent into the configuration shown in Fig. 5 and made flat or curved where the tape passes over the same. This guide is held between the body and cover of the receptacle as shown in Figs. 1 and 2 and is rigidly supported thereby to form a rigid guide for the tape passing over it. When the tape is coiled loosely the inner end is bent back on itself 105 and glued or otherwise fastened around a 110

small stick 25 as shown in Fig. 4, or the tape itself may be coiled up so as to form an enlargement which prevents the end from passing out of the receptacle and falling therefrom.

In the operation of my device liquid 13 is prepared of such a nature as to be both sticky and attractive to flies. The receptacle is suspended from the ceiling of a room or any other convenient point and tape 20 is grasped and pulled downwardly out of the receptacle. From the construction illustrated it will be evident that a downward pull upon the tape will over-turn the receptacle and thus allow the tape to be readily withdrawn therefrom. The tape upon emerging is coated with a uniform thickness of the sticky liquid on both its sides, as it passes through the liquid for a considerable distance as shown. The liquid is also provided in sufficient quantity to cover the roll of tape so that the same has ample opportunity to become coated on both sides with the liquid. The superfluous liquid adhering to the tape is scraped off and evenly distributed over the tape by means of guards 21. The tape, having been drawn out to a convenient and suitable distance, forms an object of attraction and a resting place for flies. Upon the exposed tape becoming covered with flies it is cut or torn off and a new portion of the tape withdrawn from the receptacle and exposed within the room. Enough tape is mounted within the receptacle to provide a catcher which will last for an extended period of time.

It will be seen that the weight of the roll of tape will keep the receptacle in its upright position with opening 19 above the surface of the liquid therein. Thus it is not necessary to eccentrically journal the receptacle as it may be concentrically journaled and still retain its upright position. It is preferable to do so however as the receptacle would be liable to be overturned when all or part of the tape was withdrawn therefrom.

Having described my invention what I claim as new and desire to secure by Letters Patent is:—

1. A device of the class described comprising a receptacle, said receptacle being provided with an aperture in one of its walls; a resilient guard mounted on each side of said aperture; a tape guide mounted within said receptacle; and a tape coiled within said receptacle and passing over said guide and out of said receptacle between said guards.

2. A device of the class described comprising an eccentrically mounted receptacle having an aperture in one of its walls above its bottom; spring guards mounted on each side of said aperture and forming opposite walls thereof; a tape guide mounted within said receptacle near the bottom thereof; and a

tape coiled within said receptacle and passing over said guide and out of said receptacle between said guards. 65

3. A device of the class described comprising a receptacle having an aperture in one of its walls; a frame of resilient wire mounted in said receptacle, said frame being held in place by its resilient pressure against the walls of the receptacle; and a tape coiled on said frame and passing out of said receptacle through said aperture. 70 75

4. A device of the class described comprising a receptacle having an aperture in one of its walls; resilient guards forming the sides of said aperture; a frame of resilient wire mounted in said receptacle, said frame being held in place by its resilient pressure against the walls of the receptacle; and a tape coiled on said frame and passing out of said receptacle through said aperture. 80

5. A device of the class described comprising an eccentrically mounted receptacle having an aperture in one of its walls above its bottom; spring guards mounted on each side of said aperture and forming opposite walls thereof; a frame of resilient wire mounted in said receptacle, said frame being held in place by its resilient pressure against the walls of the receptacle; and a tape coiled on said frame and passing out of said receptacle through said aperture. 85 90 95

6. A device of the class described, comprising a journaled liquid receptacle having an aperture in one of its walls above the liquid level therein; a tape guide mounted within said receptacle; and a tape coiled within said receptacle and doubling over said guide within the liquid and passing out of said receptacle through said aperture. 100

7. A device of the class described, comprising a receptacle for adhesive material, a coil of flexible material to be coated, disposed within said receptacle and adapted to be withdrawn therefrom, and a detachable resiliently supported spindle for said coil of flexible material. 105 110

8. A device of the class described, comprising a receptacle for adhesive material, a coil of flexible material to be coated, disposed within said receptacle, and adapted to be withdrawn therefrom, and a detachable 115 resiliently supported guiding means for said coil of flexible material.

9. A device of the class described, comprising a receptacle for adhesive material, a coil of flexible material to be coated disposed within said receptacle and adapted to be withdrawn therefrom, and detachable resiliently supported guiding and supporting means for said coil of flexible material. 120

10. A device of the class described, comprising a receptacle for adhesive material, a coil of flexible material to be coated disposed within said receptacle and adapted to 125

be withdrawn therefrom, and a detachable resiliently supported spindle and guiding stud for said coil of flexible material.

11. A device of the class described, comprising an apertured receptacle for adhesive material, resilient guards mounted on each side of said aperture, a coil of flexible material to be coated disposed within said receptacle and adapted to be withdrawn therefrom between said guards, and a combined

guiding and supporting means for said coil of flexible material.

In witness that I claim the foregoing I have hereunto subscribed my name this 13th day of December, 1907.
